BABY BLANKET COMBINATION

Elinor B. Shuster, Minneapolis, Minn.

Application August 13, 1948, Serial No. 43,997

4 Claims. (Cl. 128—134)

1

This invention relates to baby blanket combinations, and particularly to a combination with a baby blanket of an easily detachable mattress cover, which may be firmly anchored to the mattress, a safety belt, which is easily applied, and a washable, waterproof, though not uncomfortable, pad section.

Not much has been done in this field, to provide a baby blanket, which together with a safety belt, a waterproof pad and a mattress cover, with means holding to the mattress and the spring of a crib, may all be securely attached, though readily detached. Baby blankets have been provided, which have an opening front with slide type fasteners, and with an end and side sections secured by lacing together under the mattress. These are cumbersome to apply and remove from the mattress, and the baby may free himself from the blanket and fall on the floor. Mattresses have been made, which have a waterproof sheet and also a blanket or covering, both of which are secured by slide fasteners to the edges of the mattress and made to serve on either side, as the mattress is reversed. These attachments are available only with the mattress, which is made especially for them, and are not for use with any stock mattress, so involve considerable expense. Garments, in the nature of sleeping bags, have been made, which are however for resting out-of-doors, and are not adaptable for any general use.

An important object of my invention is to provide a baby blanket combination consisting of a blanket, a safety belt, a waterproof pad, and a mattress cover with means holding to the mattress and the spring of a crib, all of which, as a unit, may be readily and firmly adapted to a mattress, and from which unit, the blanket may be completely detached, while the balance of the unit is laundered.

Another important object is to provide such a baby blanket combination, which will afford the utmost in comfort and freedom for the baby and be easy of access, while still keeping in perfect safety.

Another object is to provide such a baby blanket combination, which can be economically manufactured and adapted to any standard baby crib mattress, without any alteration in the mattress.

Other objects will be apparent from the description and appended claims.

For a full disclosure of my invention, reference is made to the description following and to the drawing, in which—

Fig. 1 is a perspective view of my baby blanket combination, applied to an ordinary baby crib mattress, and with the blanket partly detached and folded back, to show the details.

2

Fig. 2 is a sectional view taken on the line 2—2 of Fig. 1, but with the blanket fully secured.

Fig. 3 is a sectional view taken on the line 3—3 of Fig. 1, but with the blanket fully secured.

Fig. 4 is a sectional view, on a larger scale, of the safety belt, taken through the flexible tab connection between the safety belt and the mattress cover, with the safety belt in a tipped up position, to show same more clearly.

Referring more particularly to the drawings, I provide a cover 10 of sheeting, which will fit any standard mattress for a baby's crib. This cover extends over the edge of the mattress, and has holding ends 11 extending under and around each end of the mattress. It also has straps 12, secured to the cover by stitching, and the straps have snap fasteners 13, by which attachment may be readily made to the spring of the crib. The cover 10, with its holding ends and straps, has firm anchorage to the mattress and spring, and is retained in a perfectly smooth position, without folds or wrinkles. It is, nevertheless, quickly and easily removed for changing and laundering, which is ordinarily a daily task. With only the ends of the mattress encompassed, the mattress is open underneath for ventilation, and since such mattresses are commonly reversible, the mattress may be turned daily and thus kept well aired. On the under side of the cover 10, I provide a waterproof pad 14, securely sewed at its edges to the cover. This pad is very nearly as wide as the mattress, but does not extend fully to each end thereof, and protects only the area required. This pad is made of rubberized fabric, preferably flannel, and turned so that the flannel side is up, so the cold feeling of the rubberized side is not transmitted through the sheet. The material, of which this pad is made, can be subjected to boiling water and may be washed daily for a long time without deterioration. A protective band or safety belt 15, is flexibly attached to the cover 10, by stitching at respective ends of a tab 16. This safety belt has tie strips 17, for firmly securing same, after it is wrapped around the baby. It is positioned for normal position of the baby in the crib, and the tab suspension allows for freedom of movement, but does not permit the baby to turn over. It keeps the baby in a safe position, so it does not slip under the covers and smother, which

sometimes happens without such protection. A blanket 18 is detachably secured to the cover, with slide type fasteners 19, commonly known as "zippers." Fastening of same is made in the conventional manner, by stitching the tape, to which they are attached, to the respective materials of the blanket and the cover. These fasteners secure the blanket on each side and part way across

from each side at the head of the bed, so that the baby is normally positioned and positively covered. The baby, however, is easy of access and in case of wetting, the blanket is easily detached, so the balance of the combination may be laundered. In case a quilt or additional covering is required, it is applied over the blanket and requires no fastening, as the securement of the blanket, prevents the baby from disturbing the additional covers.

From the foregoing, it is apparent how my baby blanket combination is made up, and how it must meet the needs. It keeps the baby securely though comfortably covered, it cooperates with the mattress and spring to prevent any displacement, it provides for easy access to the baby for changing purposes, it protects the mattress from damage due to wetting, it can be easily disassembled for laundering, and can be provided at a reasonable cost to fit any standard baby crib mattress.

While I have shown and described a preferred form of my invention, it is obvious that many changes, which are within the scope of my invention, will be apparent to those skilled in the art. I therefore desire to be limited only by the scope of the appended claims.

What I claim is:

1. In combination, a baby blanket, a mattress cover, a water proof pad and a safety belt; said blanket being detachably secured to said cover with slide type fasteners on each side and extending part way across from each side at the head end thereof; said mattress cover adapted to fit over the top and edges and ends of a mattress and having holding portions to encompass substantially each end of the mattress for releasable anchorage, and being provided with a plurality of straps with snap fasteners, adapted to attach to a spring of a baby crib; said waterproof pad being secured to the under side of said mattress cover and positioned substantially intermediate of the two ends of said cover; said safety belt comprising a band adapted to fit around the chest of a baby, a plurality of tie strips secured at one end and on the outside of said band a substantial distance from the other end of said band, so as it encompasses the baby's chest a portion is provided toward the inside and under the tying of said tie strips, and a narrow tab secured at the ends and flexibly joining said band to the top of said mattress cover substantially medially of the width of said cover, and at a location lengthwise to position a baby within said blanket, said safety belt by reason of said tab and said tie strips allowing freedom of movement but not permitting the baby to turn over.

2. A baby blanket combination, comprising a mattress cover adapted to fit over the top and edges and ends of a mattress and having holding portions to encompass substantially each end of the mattress for releasable anchorage and having means for attaching to a spring of a baby crib; a blanket detachably secured to said cover with slide type fasteners on each side and extending part way across from each side at the head end thereof; a waterproof pad secured to the under side of said mattress cover and positioned substantially intermediate of the two ends of said cover; and a safety belt formed of a band adapted to fit around the chest of a baby, with means to secure said band, so that said band is a continuous wrapping under said means, and with a narrow tab secured at the ends and flexibly joining said band to the top of said mattress cover sub-

stantially medially of the width of said cover, and at a location lengthwise to position a baby within said blanket, said safety belt by reason of said tab and said tie strips allowing freedom of movement but not permitting the baby to turn over.

3. In a device of the character described, in combination; a mattress cover adapted to fit over the top and edges and ends of a mattress and having holding portions to encompass substantially each end of the mattress for releasable anchorage, and being provided with a plurality of straps with snap fasteners adapted to attach to a spring of a baby crib, and having washable waterproof means secured to a substantial area on the under side thereof to protect the mattress without discomfort to the baby; a blanket detachably secured to said cover with slide type fasteners on each side and extending part way across from each side at the head end thereof; and a safety belt comprising a band adapted to fit around the chest of a baby, a plurality of tie strips secured at one end and on the outside of said band, so as it encompasses the baby's chest a portion is provided toward the inside and under the tying of said tie strips, and a narrow tab secured at the ends and flexibly joining said band to the top of said mattress cover substantially medially of the width of said cover, and at a location lengthwise to position a baby within said blanket, said safety belt by reason of said tab and said tie strips allowing freedom of movement but not permitting the baby to turn over.

4. A baby blanket combination, comprising a mattress cover adapted to fit over the top and edges and ends of a mattress and having holding portions to encompass substantially each end of the mattress for releasable anchorage, and being provided with a plurality of straps with snap fasteners adapted to attach to a spring of a baby crib; a waterproof pad secured to the underside of said mattress cover and positioned substantially intermediate of the two ends of said cover; a safety belt formed of a band adapted to fit around the chest of a baby and having a plurality of tie strips secured at one end and on the outside of said band a substantial distance from the other end of said band, so as to encompass the baby's chest and providing a portion toward the inside and under the tying of said tie strips, and having a narrow tab with the ends thereof secured to and flexibly joining said band to the top of said mattress cover substantially medially of the width of said cover, and at a location lengthwise to position a baby in a crib, and by reason of said tab and said tie strips allowing freedom of movement but not permitting the baby to turn over; and a blanket with means detachably securing said blanket to said mattress cover on each side and extending part way across from each side at the head end thereof sufficiently to cover the baby's shoulders, and permitting covers to be added without being disturbed, due to restraint of the blanket by said means.

ELINOR B. SHUSTER.
